United States Patent Office.

AMOS P. WILLARD, OF BATTLE CREEK, MICHIGAN.

Letters Patent No. 94,263, dated August 31, 1869.

IMPROVED MEANS FOR PUTTING UP AND USING POWDERS.

The Schedule referred to in these Letters Patent and making part of the same.

To all whom it may concern:

Be it known that I, AMOS P. WILLARD, of Battle Creek, in the county of Calhoun, and State of Michigan, have invented a new and useful Improvement in Method of Putting Up and Using Powders; and I do declare that the following is a true and accurate description thereof, reference being had to the accompanying drawings, and to the letters of reference marked thereon, and being a part of this specification.

The nature of this invention relates to the construction of a suitable box, within which to put up any soluble coloring-matter, so that by dipping the box in water, a sufficient amount of coloring may be extracted from the box by dissolving said coloring-matter.

The invention consists in a wooden cup or circular box, provided with a handle, said cup or box being turned from one piece of wood, and designed to hold soluble coloring-matter, such as a compound of soluble bluing and oxalic acid, or other similar matter, which is held and confined in said cup or box by means of a piece of muslin or other thin textile fabric, tied or otherwise secured over the open end of the cup or box.

In the drawings—

A represents a cup or circular box, provided with

handle B, both cup and box being turned or worked from one piece of timber.

Over the open end of this cup is drawn tightly a piece of muslin, C, or other thin textile fabric, for the purpose of retaining the contents of said cup in place, and of allowing them to escape only when dissolved. This piece of muslin may be secured by tying or in any other suitable way.

The box or cup being filled, for instance, with soluble bluing and oxalic acid, in proper proportions, the muslin should be tied on. Then grasping the handle, the operator immerses the cup in a tub of water, and stirs the same about until the requisite amount of color has been imparted to the water by the dissolving of the compound escaping through the muslin.

What I claim as my invention, and desire to secure by Letters Patent, is—

As a new article of manufacture, the cup A and handle B, when both are worked from one piece of timber, and provided with the muslin cover C to the cup, substantially as and for the purposes set forth.

AMOS P. WILLARD.
